UNITED STATES PATENT OFFICE.

METHOD J. HYNEK, OF CHICAGO, ILLINOIS.

DESIGN FOR A BADGE.

No. 39,986.

Specification for Design.

Patented May 18, 1909.

Application filed March 24, 1909. Serial No. 485,549. Term of patent 3½ years.

Be it known that I, METHOD J. HYNEK, a citizen of the United States, residing at Chicago, Cook county, Illinois, have invented a new, original, and ornamental Design for Badges, of which the following is a specification, reference being had to the accompanying drawing, forming part thereof.

The figure is a plan view of a badge showing my new design.

I claim:
The ornamental design for a badge as shown.

METHOD J. HYNEK.
